UNITED STATES PATENT OFFICE.

NORMAN W. LYON, OF SPRINGFIELD, MASSACHUSETTS, ASSIGNOR TO EDWARD O. SUTTON, OF SPRINGFIELD, MASSACHUSETTS.

BURNER.

Application filed September 7, 1923. Serial No. 661,518.

This invention relates generally to improvements in burners and, while the invention, according to many of its features, is capable of general application, it finds one 5 advantageous use in connection with burners intended for household use.

Furnaces, in which oil, or other liquid fuel is burned, are usually provided with a pump to feed the oil, a blower to force in 10 air, an electric motor to operate the pump and blower and a pilot light, usually a gas flame, to ignite the fuel. Installations of this type require, in addition to the essential oil piping, gas piping for the pilot light 15 and electric wiring for the electric motor. There is thus an undesirable dependence on the public service companies, which supply the gas and electricity, and a failure of either interrupts the operation of the furnace. 20 Moreover, due to the use of gas and electricity there are many checks and safeguards which are required by the underwriters to be used in connection with such installations and these tend to complicate the apparatus 25 and add to the cost thereof. Installations of the type described are relatively expensive.

One object of this invention is to provide a comparatively simple installation for the 30 purpose described which is far less expensive than the usual one, as above set forth, and which eliminates the electrical and gas connections and the undesirable dependence on the supply of gas and electricity.

More particularly, the invention contemplates the provision of an internal combustion engine for driving air and fuel forcing 35 devices and an arrangement, whereby the engine operates from part of the fuel and air supplied to the furnace.

It is also an object of the invention to provide means whereby the exhaust of the engine serves to ignite the fuel issuing from the burner.

Another object of the invention is to provide an arrangement for a heat exchange between the engine and the air supplied to the furnace, whereby the engine may be cooled, and the air preheated prior to its mixture 50 with the fuel.

According to the features of the invention, as above set forth, the installation is such as to require no gas piping or electric wiring and there is dependence on a supply of fuel only. Also no valves are necessary in the 55

oil and gas lines and no switches in the electrical connections, as is usual in installations of the type first above set forth. On cranking the engine, the supply of air and oil automatically starts and on stopping the engine, the supply of these elements automatically stops. The engine requires no special ignition devices and the pilot flame, being the exhaust flame from the engine, is automatically extinguished when the engine 60 stops and thus offers no fire hazard.

Other objects and advantages will appear in the following description and in the illustrative embodiment of the invention in the accompanying drawings, in which, 70

Fig. 1 is a sectional elevational view of an internal combustion engine embodying the invention and also showing parts associated therewith for use in connection with furnace installations; 75

Fig. 2 is a cross sectional view of the engine, taken longitudinally through its cylinder;

Fig. 3 is an end elevational view illustrative of the fuel forcing means; 80

Figs. 4 and 5 are cross sectional views taken on the lines 4-4 and 5-5, respectively of Fig. 1;

Fig. 6 is a diagrammatical view illustrative of the fuel supply connections; and 85

Fig. 7 is a fragmentary sectional plan view taken on the line 7-7 of Fig. 1.

Referring to these drawings;—the engine is of the single cylinder, two-cycle type and is entirely enclosed within a casing A (Fig. 1), which is of generally cylindrical shape and is centrally divided intermediate its ends into two parts 10 and 11. These parts preferably interfit, as at 12, and are suitably secured together, as by bolts 13 (Fig. 2). 90 The casing sections 10 and 11 are provided with aligned openings 15 to receive and support the engine parts within the casing A and the latter is provided with removable plugs 16 and 17 to permit, respectively, the filling and draining of oil. The casing is otherwise entirely closed and it is intended to be filled with oil, whereby all moving parts of the engine may be automatically lubricated, in a manner to be described.

Mounted in each opening 15, and suitably fixed to casing A, is a sleeve 20, and fixed to each sleeve, as by being formed integrally therewith, as illustrated, or otherwise, are two eccentrics 21 and 22, which are disposed 100

entirely within casing A and adjacent the end walls thereof. The centers of eccentrics 21 and 22 are located on opposite sides of the axis of openings 15. The eccentrics 21 5 rotatably receive members which carry the piston of the engine and the eccentrics 22 rotatably receive members which carry the cylinder of the engine.

The driven member of the engine consists 10 of a hollow shaft 23 rotatably mounted near its ends in the sleeves 15, already described. This hollow shaft is flanged, as at 24, near each of its bearings and the flanged portions coact with the end faces of the adjacent eccentrics 22 to limit the end play of the shaft. Intermediate its ends, the shaft is enlarged 15 and formed to provide a cylinder 25 which is closed at one end by an integral head 26 and which is open at the opposite end to slidably 20 receive an engine cylinder 27.

The relative reciprocating movement of cylinders 25 and 27, as will later appear in detail, is made to control the admission of air and fuel to the engine cylinder 27. Air 25 is supplied into the left hand end of the hollow shaft 23 (as viewed in Fig. 1) and fuel is supplied through a pipe 28, which is secured to the cylinder 25 and extends outwardly through shaft 23 in spaced concentrical relation therewith. An annular recess 29 is formed in the interior wall of cylinder 25 to receive the fuel from pipe 28 and leading from this recess is a second pipe 30 which is secured to cylinder 25 and ex- 30 tends outwardly therefrom through right hand portion of shaft 23 (as viewed in Fig. 1) in axial alignment with pipe 28. The interior of the right hand portion of shaft 23 is connected to the left hand portion 35 thereof by a cored passage 31 which encompasses cylinder 25 and forms a cooling jacket therefor, as will appear.

The cylinder 27 is closed at one end by an integral head 32 and at the opposite end, 40 which is flanged, as at 33, by a removable head 34 which overlies the flange. A member 35 has a circular opening to closely fit the outer wall of cylinder 27 and this opening is counterbored to receive the flange 33 and head 34 and the head, flange and member 35 are suitably secured together, as by bolts 36 (Fig. 7). The member 35, at diametrically opposite points, is provided with trunnions 37 which are pivotally received 45 in ring-like members 38, located on opposite sides of cylinder 27. The members 38 are interconnected at angularly spaced points by spacers 39 to which the members are attached by cap screws 40. The members 38 50 are rotatably mounted on the eccentrics 22. The piston is shown at 41 and it is rigidly attached by a cap screw 42 to a piston rod 43. The piston is otherwise of conventional 55 form and is supplied with suitable rings, indicated at 44. The piston rod is slidably

received in head 34; passes therethrough; and at its outer end is enlarged, as at 46, to provide for the reception of a pin 45 disposed with its axis transverse to that of the rod. The ends of pin 45 project beyond 70 said enlarged portion and are shouldered down to form trunnions 47 which are received one in each of two ring frame members 48. The latter are rotatably mounted on the eccentrics 21, one on each, and extend 75 toward one another into abutting relation and are joined together, as by bolts 49. Various openings, such as 50, are however provided in the members 48 so that oil can 80 freely enter therein from casing A.

As usual in two cycle engines, provision is made for admitting air beneath the pistons, or more properly in this case, to that space in cylinder 27 opposite from the combustion chamber, and the cylinder 27 is closed by 85 the head 34 for this purpose, just as the crank case of an ordinary two cycle engine is closed. To accomplish this object a port 51 is provided in the wall of cylinder 25 to connect with the interior of shaft 23 and a port 52 is provided on the wall of cylinder 27 in such position as to register with port 51 when, as illustrated, the piston and cylinder 27 are in firing relation. On firing, which is accomplished by high compression, 90 and the heat generated thereby, the piston 41 and cylinder 27 move in opposite directions and the port 52 is soon covered by the piston and ports 51 and 52 soon moved out of registry to cut off the air supply and allow the air drawn in on the previous stroke to be compressed.

For transferring the air thus compressed into the combustion chamber at the opposite end of cylinder 27, a series of grooves 53 105 (Fig. 2) are formed in the walls of cylinder 27, which grooves extend from head 34 part way toward the opposite end of the cylinder and sufficiently far so that the extremities will communicate with the combustion chamber near the end of the firing stroke.

For exhausting or scavenging, a port 54 is formed in cylinder 27 which is adapted at the proper time to communicate on one side with the combustion chamber and on the other side with a port 55 formed in the wall of cylinder 27 and communicating with the air passage 31. On the explosion stroke, as the cylinder 27 and piston move in opposite directions, the port 54 will, near the end of such stroke move into registry with port 55 and will be uncovered by the piston so as to communicate with the combustion chamber. The scavenging, as usual, is aided by the inrushing of compressed air which occurs at substantially the same time. Shortly after the start of the compression stroke, the ports 54 and 55 will move out of registration.

The fuel, which may be crude oil or other 130

combustible substance, is, as described, supplied to the annular passage 29. Measured charges of the fuel are taken from this recess during the firing stroke and later, near the end of the compression stroke, atomized by compressed air and injected therewith into the combustion chamber. To this end a recess 56 (Fig. 2) is formed in the outer periphery of cylinder 27 and this recess is connected by a small orifice 57 with the interior of the cylinder. On the firing stroke, the cylinder will move so that recess 56 is carried toward and finally into communication with passage 29 and the recess will be filled with a measured volume of fuel. At the same time, the orifice will be closed by the piston, which has moved in an opposite direction to the cylinder. As the cylinder 27 and piston move toward one another on the compression stroke, the recess 56 will be carried into registry with a passage 58 formed in member 25 and the orifice 57 will be brought into registry with an inclined passage 59 formed in piston 41 and leading to a circumferential groove 60 in the described cap screw 42. Communicating with groove 60 and leading from the latter to the head of the piston, are a series of longitudinal grooves 61 formed in the periphery of the cap screw 42, whereby communication between the combustion chamber and passage 59 is established. The passage 58 is supplied with air under pressure, as will be described, and when this passage, communicates with recess 56 and passage 59 communicates with orifice 57, the measured charge of fuel in recess 56 will be mingled with the compressed air from passage 58 and injected at high velocity into the combustion chamber. The passage of the oil in this manner and through the small orifice 57 and the grooves 60 and 61 insures a breaking up of the fuel and an adequate atomizing of the latter.

The passage 58, described, intersects with a passage 63, which terminates in a chamber 64. A port 65 connects this chamber to the interior of cylinder 25 at a point adjacent to head 26 and beyond the range of travel of cylinder 27. A spring pressed ball check valve 66 controls the communication between the cylinder 25 and chamber 64 and permits air to enter to the latter from the former but prevents return flow. Air is supplied to the clearance space of cylinder 25 by a port 67 which connects such space with the interior of shaft 23, when the cylinder 27 occupies the illustrated position. The cylinder 27 functions as a piston in cylinder 25 and air, admitted to the clearance space of the latter through port 67, is compressed and forced past check valve 66 into the passages 63 and 58 and chamber 64, thus filling the latter with air under a considerable pressure, for use in the manner heretofore described.

The cylinder 27 on its return stroke creates

a partial vacuum in the clearance space of cylinder 25, whereby to draw in a fresh charge of air, when such space is again placed in communication with the interior of shaft 23, which occurs when the cylinder 27 occupies the illustrated position.

Connected with the shaft 23 is a suitable fly-wheel, or the equivalent thereof, and in the present case a hand wheel 69 serves this purpose and is also used as a means for starting the engine. The wheel 69, as illustrated, is attached by cap screws 70 to a fan rotor 71, having blades 72, such rotor being secured to shaft 23, as indicated. The fan rotor is not necessarily essential so far as the engine itself is concerned, although it may be used to advantage therewith. The fan, however, is needed where the engine is used in connection with oil burning furnaces as will later appear.

On turning the hand wheel 69, cylinder 25, being a part of shaft 23, rotates and thus turns cylinder 27, which causes carrier 38 to revolve around eccentrics 22 and thus about an axis parallel, but spaced from shaft 23, the cylinders 25 and 27 having relative axial freedom for this purpose. Similarly, the cylinder 27 in revolving turns piston rod 43 with it, thereby causing carriers 48 to revolve around eccentrics 21, and thus about an axis which is spaced from both the axis of eccentrics 22 and the axis of shaft 23 but which is parallel therewith. The piston rod 43 and cylinder 27 have relative axial freedom to permit this rotation and the trunnions 47 and 37 permit such slight rocking movements as are necessary during the movements described. By turning the hand wheel 69, as described, the engine parts are reciprocated and charges of air and atomized fuel are drawn into the combustion chamber and, being highly compressed, the charges are ignited from the heat of the compression. The explosion tends to move cylinder 27 and rod 43 in opposite directions, and except when the parts are in the illustrated position wherein a "dead center" condition occurs, the relative axial movements of these parts move their respective carriers around their respective eccentrics and the cylinder 27, when thus rotated, causes cylinder 25 and thus shaft 23 to revolve.

In order to adapt the engine for use in connection with oil burning furnaces, the pipe 30 and the right hand portion of the hollow shaft 23 are used to supply the oil and air respectively, and the ends of both are adapted for insertion in an opening in the furnace. The pipe 30 is provided with a cap 73 having a plurality of angularly spaced orifices 74 to emit the oil in a plurality of jets at right angles to the direction of the air travelling through hollow shaft 23 and thereby secure a good atomization of the fuel. Encompassing the end of shaft 130

23 is a ring like member 75 of frusto conical shape. Ignition of the fuel issuing from orifices 74 is effected without the aid of any special ignition means, such as the usual 5 pilot light, by the flame issuing from the exhaust of the engine into shaft 23.

The fan rotor 71 is mounted in a suitable two part casing consisting of two members 75 and 76 suitably secured together as by 10 bolts 77 and the casing member 75 preferably is provided with stationary vanes 78 to prevent the air from swirling. The air enters at 79 and is expelled into the open left hand end of the hollow shaft 23. As 15 shown, the volume of air designed to be supplied to shaft 23 is sufficient to supply the needs of the engine and the furnace and, in case the furnace is not used, the fan, if used, as it may be, would be made much smaller 20 as it would then have to supply only the engine.

The fan casing is stationarily supported together with casing A from a suitable bed plate 80 which has upstanding flanges 81 to 25 which the casings are secured, as by bolts 82.

The fuel is delivered to pipe 28 by a gear pump comprising intermeshing spur gears 83 and 84, the former having an integral hollow shaft 85 which connects with pipe 28 30 and is rotated thereby, both being fixed to a coupling 86. The gears 83 and 84 rotate in a suitable recess formed in a member 87, which is secured, as by cap screws 88, to an end face of casing 75, and the latter serves 35 as one wall of the gear pump chamber. The shaft 85, and the shaft 89 for gear 84, are supported at their ends in the member 87 and the adjacent wall of casing 75. Fuel is supplied by a pipe 90 (Fig. 6) from a reservoir 91, to an inlet passage 92 (Fig. 3) in member 87. The fuel drawn into this passage 92 by suction is expelled by the gears 83 and 84 into a similar passage 93, also formed in member 87. Connected with passage 93 is a discharge pipe 94 (Fig. 6) which leads back to the fuel reservoir 91 and has interposed therein, a suitable relief valve 95, which permits oil to be forced into reservoir 91 after the pump has built up a predetermined pressure. The passage 93 also connects with an opening 96 in the casing 75 and the opening 96 is connected by a cored passage 97 to an opening 98, also in casing 75 (see Fig. 5). The opening 98, as shown 55 in Fig. 1 is connected to a chamber 99 in member 87 and a passage 100 leads from this chamber to shaft 85, such passage being controlled, as by a needle valve 101, which may be operated in any suitable manner, as thermostatically for example. Thus, oil may be continuously supplied at a predetermined pressure to the engine and the nozzle 73 of the furnace.

The operation will largely appear from

the foregoing description and need be only briefly summarized. The engine, being started, as described, the gear pump and fan are set in motion and air and fuel (the latter at a predetermined pressure) are forced through shaft 23 and pipe 28. Part of the air and part of the fuel are utilized by the engine and the remainder passes through the right hand portion of shaft 23 and pipe 30 to the furnace. The atomized fuel for use in the furnace is ignited by the flame from the exhaust of the engine.

When the engine stops the supply of fuel and air automatically stops and the furnace flame soon becomes extinguished. When the engine is again started, the fuel and air are automatically supplied to the engine and furnace without operating any valves and the ignition of atomized fuel for both engine and furnace is automatically accomplished without special ignition devices, such as those of an electrical character for the engine. The installation is thus an extremely simple one and relatively inexpensive, especially so, since the usual gas piping and electric wiring are eliminated together with the many checks and safeguards required in the usual furnace installation. Dependence on gas and electricity, either of which may fail, temporarily at least, is entirely avoided and a simple, reliable and comparatively inexpensive installation is provided, which performs all the work of the more complicated and expensive installations and is substantially fool proof and safe. All that is necessary is to crank the engine and the rest is automatic.

It should be particularly noted that the air, and the fuel for that matter, are heated prior to delivery to the furnace by their passage around the engine and thereby placed in condition for a more satisfactory atomization than would otherwise be the case. Also the engine is cooled at the same time and a heat exchange is effected to the advantage of both the engine and furnace. Air for cooling the engine is not only admitted below the piston but also above it and the head 32 of cylinder 27, thereby effectively cooling the engine parts and heating the air subsequently supplied to the engine.

As to the engine, apart from its use in connection with furnaces, there are many important and distinctive features which should be noted. All the rotary parts of the engine are balanced as far as their axes of rotation are concerned. The cylinder 25 is balanced around its axis of rotation, being that of shaft 23. The cylinder 27 and connected parts are likewise balanced about an axis passing through the center of eccentricities 22 and finally, the piston, its rod and connected parts are balanced about an axis passing through the centers of eccentricities 21. All

moving parts are automatically lubricated from the supply of lubricant contained in casing A.

The use in a two cycle engine of means for measuring out a predetermined charge of fuel by taking a definite volume at a definite pressure on each stroke of the engine and later injecting such charge by heated air, previously compressed to a high degree, is considered an important feature. Also the ordinary two cycle engine seldom gets a full volume of air in the crank case and the compression cannot be maintained readily at as high degree as is desired here. A full supply is insured in the present case by the arrangement for forcing it by the fan into the cylinder 27 below the piston, as distinguished from merely relying on suction, and by the secondary supply of air supplied above the head 32 of cylinder 27. This secondary supply of air is heated and compressed prior to its injection into the combustion chamber and serves also to atomize and inject the measured charge of fuel as above set forth. The invention has been disclosed herein, in an embodiment at present preferred, for illustrative purposes, but the scope of the invention is defined by the appended claims rather than by the foregoing description.

What I claim is:—

1. In combination, an internal combustion engine, and fuel and air supply conduits having connections therewith and extending therebeyond, said engine having a connection through which its exhaust is delivered to ignite the fuel emitted from said fuel conduit.

2. In combination, a fuel conduit, an air conduit, means for forcing fuel and air through their respective conduits, an engine for driving said means and operating from a part of the fuel and air forced through said conduits, and means whereby the exhaust of the engine is delivered to ignite the fuel emitted from said conduit.

3. In combination, a high compression internal combustion engine of the type where- in the charge is ignited by the heat of compression, an oil burner conduit, an air conduit in connection therewith, fuel and air forcing devices driven by said engine, connections whereby a part of the oil and air is supplied to said engine for operating the same, and connections whereby the exhaust of the engine is so delivered and directed as to ignite the fuel emitted from said first named conduit.

4. In combination, a high compression internal combustion engine of the type where- in the charge is ignited by the heat of compression, an oil burner conduit, an air conduit in connection therewith, an air forcing device driven by said engine, connections whereby a part of the oil and air is supplied to said engine for operating the same, and

connections whereby the exhaust of the engine is so delivered and directed as to ignite the fuel emitted from said first named conduit.

5. In combination, a high compression internal combustion engine of the type where- in the charge is ignited by the heat of compression, an oil burner conduit, an air conduit in connection therewith, an oil forcing device driven by said engine, connections whereby a part of the oil and air is supplied to said engine for operating the same, and connections whereby the exhaust of the engine is so delivered and directed as to ignite the fuel emitted from said first named conduit. 70

6. In combination, a high compression internal combustion engine of the type where- in the charge is ignited by the heat of compression, an oil burner conduit, an air conduit in connection therewith, connections whereby a part of the oil and air is supplied to said engine for operating the same, and connections whereby the exhaust of the engine is so delivered and directed as to ignite the fuel emitted from said first named conduit. 85

7. In combination, a high compression internal combustion engine of the type where- in the charge is ignited by the heat of compression, an oil burner conduit, an air conduit in connection therewith, fuel and air forcing devices driven by said engine, and connections whereby a part of the oil and air is supplied to said engine for operating the same. 90

8. In combination, a burner, fuel and air supply conduits therefor, means for drawing fuel and air therethrough, an internal combustion engine for operating said means, said conduits being arranged to conduct the fuel and air adjacent to said engine, whereby said engine is cooled and the air and oil is warmed prior to its delivery to said burner, and connections between said conduits and engine to enable the latter to operate from a part of the fuel and air fed through the former. 105

9. In combination, a burner, fuel and air supply conduits therefor, means for inducing flow of fuel and air in their respective conduits, an internal combustion engine for driving said means, and means for drawing measured quantities of fuel from said fuel conduit and supplying it to said engine for 110 operating the same. 115

10. In combination, a burner, fuel and air supply conduits therefor, means for inducing flow of fuel and air in their respective conduits, an internal combustion engine for driving said means, and means for drawing measured quantities of fuel and air from said conduits and supplying said charges to said engine for operating the same. 120

11. In combination, a burner, fuel and air 130

supply conduits therefor, means for inducing flow of fuel and air in their respective conduits, an internal combustion engine for driving said means, and means for drawing measured quantities of fuel from said fuel conduit, means for withdrawing a measured charge of air from said air conduit and delivering such charge adjacent to said engine to preheat the same, and means for subsequently mixing said charges and delivering them to said engine.

12. In combination, an internal combustion engine, an oil burner conduit, an air conduit in connection therewith, an air forcing device driven by said engine, connections whereby a part of the oil and air is supplied to said engine for operating the same, and connections whereby the exhaust of the engine is so delivered and directed as 20 to ignite the fuel emitted from said first named conduit.

13. In combination, an internal combustion engine, an oil burner conduit, an air conduit in connection therewith, an oil forcing device driven by said engine, connections

whereby a part of the oil and air is supplied to said engine for operating the same, and connections whereby the exhaust of the engine is so delivered and directed as to ignite the fuel emitted from said first named conduit.

14. In combination, an internal combustion engine, an oil burner conduit, an air conduit in connection therewith, connections whereby a part of the oil and air is supplied to said engine for operating the same, and connections whereby the exhaust of the engine is so delivered and directed as to ignite the fuel emitted from said first named conduit.

15. In combination, an internal combustion engine, an oil burner conduit, an air conduit in connection therewith, fuel and air forcing devices driven by said engine, and connections whereby a part of the oil and air is supplied to said engine for operating the same.

In testimony whereof I have affixed my signature.

NORMAN W. LYON.
